UNITED STATES PATENT OFFICE

168,885

BOTTLE

Philip Fischer, Northfield, Ill.

Application August 30, 1952, Serial No. 21,265

Term of patent 14 years

(Cl. D58—8)

To all whom it may concern:

Be it known that I, Philip Fischer, a citizen of the United States of America and a resident of Northfield, Cook County, State of Illinois, have invented a new, original, and ornamental Design for a Bottle, of which the following is a specification, reference being had to the accompanying drawing, forming a part hereof:

Fig. 1 is an elevational view of a bottle, showing my new design;

Fig. 2 is a top plan view of the same;
Fig. 3 is a bottom plan view of the same.

I claim:

The ornamental design for a bottle, as shown.
PHILIP FISCHER.
